DESIGN FOR AN ELECTRICAL APPARATUS CABINET

Bennie O. Browne, Maplewood, N. J., assignor to
Bell Telephone Laboratories, Incorporated,
New York, N. Y., a corporation of New York

Application January 5, 1935, Serial No. 54,730

Term of patent 14 years

To all whom it may concern:

Be it known that I, Bennie O. Browne, a citizen of the United States of America, residing at Maplewood, in the county of Essex and State of New Jersey, have invented a new, original, and ornamental Design for an Electrical Apparatus Cabinet, of which the following is a specification, reference being had to the accompanying drawings, forming a part thereof.

Fig. 1 of the drawings is a view in perspective of the cabinet and showing my new design. Fig. 1 shows the front and one of the side portions of the cabinet.

Fig. 2 is an elevational view of the back of the cabinet. Fig. 2 shows a plurality of doors on the back of the cabinet. Fig. 2 is drawn to a reduced scale relative to Fig. 1; and

Fig. 3 is a top plan view of the cabinet with the cabinet in the same relative position as in Fig. 2. Fig. 3 is drawn to the same scale as Fig. 2.

I claim:

The ornamental design for an electrical apparatus cabinet, as shown.

In witness whereof I hereunto subscribe my name this 5th day of January, 1935.

BENNIE O. BROWNE.
